UNITED STATES PATENT OFFICE.

LOUIS GODDU, OF WINCHESTER, MASSACHUSETTS, ASSIGNOR TO GORDON MCKAY, OF NEWPORT, RHODE ISLAND, AND JAMES W. BROOKS, OF CAMBRIDGE, MASSACHUSETTS, TRUSTEES.

NAILING-MACHINE.

SPECIFICATION forming part of Letters Patent No. 288,423, dated November 13, 1883.

Application filed September 11, 1883. (No model.)

To all whom it may concern:

Be it known that I, LOUIS GODDU, of Winchester, county of Middlesex, State of Massachusetts, have invented an Improvement in 5 Nailing-Machines, of which the following description, in connection with the accompanying drawings, is a specification, like letters on the drawings representing like parts.

This invention is an improvement on the 10 machine represented in United States Letters Patent No. 265,227, granted to me September 26, 1882, to which reference may be had.

My invention, hereinafter set forth, relates principally to means for feeding the nails intermittently and singly from the roadways of 15 the chute to the driver-passage, to be struck by the driver, and, as herein shown, I have represented the apparatus as adapted to feed nails at will from either of two chutes; but it 20 is obvious that my improved conical carrier may operate in a machine having but one roadway. In this invention the roadways, one or more, are provided each with a cone-like screw-threaded carrier, the cones being 25 pointed toward or having their smallest ends directed toward the nail-feeding drum, a part of the threaded periphery of each carrier being extended laterally into a roadway, so that the shank of a nail may be caught by the 30 smallest end of the conical carrier, the latter, by its intermitting rotation, causing the shank of the said nail to gradually travel along between the threads at the periphery of the said carrier and be delivered from its base end 35 under the driver-passage. The pitch of the threads of the conical carrier and the size of the same transversely is such that the space between the threads at the base of the said carrier, just as the carrier brings the head of 40 the nail under the driver, makes a space large enough for the reception of part of the driver and forms part of the passage-way for the descent of the driver. The carrier herein shown has five threads, its diameter being sufficient to receive that number of threads of 45 the required pitch to carry the nails in proper position from the roadway under the driver. The threads are increased in number because

of the slowness of rotation of the carrier as compared with that of the usual driver-actuating shaft; but it is obvious that the said carrier may have more or less threads than five.

This invention consists, essentially, in the combination, with the roadway or chute of a 50 nailing-machine, of a conical separator or carrier having its screw-threaded periphery projected into one side of the said roadway in such manner as to permit the nails to come upon the smallest end thereof and enter its 55 threads singly, as will be described, the said conical separator carrying the nails singly to the driver-passage and there discharging them.

My invention also consists in the said conical carrier combined with mechanism, as will 60 be described, for moving it.

Figure 1 is a partial front view of a sufficient portion of the machine represented in the said patent to enable one conversant therewith to understand my present invention. 70 Fig. 2 is an enlarged view of the right-hand side of Fig. 1, partially broken out; Fig. 3, a section of Fig. 1 on the dotted line $x-x$, but enlarged; Fig. 4, a detail of the conical separator and carrier detached, and Fig. 5 details 75 of the pawl-and-ratchet contrivance for turning the shaft of the conical separator and carrier.

In the drawings, the vibrating head B, the driver-bar a , the nail-receiving drum E, the 80 chute m , lever n , the stops f^3 f^4 , tube f^5 , spring-pressed pin f^7 therein, throat e , and shaft C are substantially the same as in my said patent, wherein mechanism is shown for actuating them, and their operation is fully explained.

The rotating shaft C has attached to it a double cam-hub, A, it having two cam-faces, 2 3. The cam-face 3 acts on a roller-stud, 4, of an arm, 5, having a stud, 6, fast to it, and 90 extended through a hole in the head B, where it has fast upon it a sector, 7, the teeth of which engage a gear-like pawl-carrier, 8, loose on the hub of a ratchet, 9, (see Fig. 5,) pinned to the shaft 10 by a pin, 11, the said shaft being extended diagonally through the nose and

into the chute parallel with the center line of the roadway therein. The shaft 10 has fast upon it the conical separator and carrier 13, herein shown as provided with five threads, 5 the pitch and size of which is right to bring the nails 14 rapidly from the roadway of the chute into position under the usual driver shown in the said patent, the said conical separator receiving the nails singly between the 10 threads at its small end, and gradually moving the said nails along the said roadway between it and the face of the wall 15 of the chute; but as the nail reaches the end of a groove, 16, it will have been carried perpendicularly under 15 the driver and into the driver-passage, so that the driver in its descent will strike the said nail and drive it, the thread of the screw forming at such time a part of the driver-passage. Just as the nail is removed from the screw by 20 the driver the front end, 17, of a thread will be in the proper position with relation to the nails in the chute to permit one of them to enter or jar well into the said thread.

The conical screw-threaded-separator and 25 carrier is rotated in the direction of the arrow thereon, or upward with relation to the roadway, thus obviating all tendency of the nails to bind or stick in the roadway. Moving the separator in such direction causes the nails to 30 travel very freely along the roadway, and a part of the friction on the roadway due to the gravity of the nail is thus overcome.

The pawl-carrier 8 has a pawl, 20, acted upon by a spring, 21, which keeps it in engagement with the ratchet 9, and the latter or the 35 shaft 10 will in practice have a suitable friction device to prevent the motion overrunning.

I have herein shown the chute as provided with two roadways, 22 23, each to receive nails 40 of the proper width.

Having described the operation of one set of devices to feed the nails along in the roadway 23, it will be understood with like devices in the other roadway, 22, that the same operation 45 of nail-feeding will be carried on in that roadway of the chute if it is desired to take nails from it. I have herein marked the corresponding devices with the same figures in connection with the letter *x*. If the roadway 23 and separator and carrier 13 are to operate, the sleeve 50 *f*⁸, common to the said patent, will be turned to cause the stop *f*⁴ to lock the arm 5^x away

from the cam 2, as in Fig. 3; but if the separator and carrier 13^x is to be the feeder of the 55 nails from the roadway 22, then the said sleeve *f*⁸ will be turned to enable the stop *f*³ to move inward far enough to arrest the inner edge of the said arm and prevent it from being drawn against the cam 3 by the spring B⁴, common to both arms 5 5^x. The chute is jointed to the 60 nose *c* by the bolt 30. The ratchet 9 has one tooth for each thread of the screw 13. Each movement of the screw 13 carries the nail for a distance equal to its diameter.

I claim—

1. In a nailing-machine, a chute and roadway therein, combined with a conical screw-threaded separator and carrier, substantially as shown and described, to operate substantially as described.

2. In a nailing-machine, a chute and roadway therein for nails, and a throat having a nail and driver passage, combined with a rotating conical screw-threaded separator and carrier, substantially as shown and described, 75 adapted to receive a nail in the said roadway and carry it positively and deliver it at or into the driver-passage, substantially as described.

3. In a nailing-machine, a chute and a roadway therein, combined with a conical screw-threaded separator and carrier having a rotation in an upward direction with relation to the vertical walls of the roadway, substantially as described.

4. The head B, shaft C, suitable cam thereon, connected arms 5 7, pawl and ratchet shaft 10, and conical screw 13, combined with the chute and its roadway, and nose *c*, to operate substantially as described.

5. In a nailing-machine, a chute, two roadways, and two conical threaded screws, 13 13^x, arranged therein as shown and described, and their shafts 10 10^x, combined with means, substantially as set forth, to operate either of the said screws intermittently to feed nails from either chute at will.

In testimony whereof I have signed my name to this specification in the presence of two subscribing witnesses.

LOUIS GODDU.
